DRAW CURTAINS AND THE LIKE

Vianney J. Dionne, Fair Lawn, N.J., assignor, by mesne assignments, to Midland-Ross Corporation, Cleveland, Ohio, a corporation of Ohio

Filed Apr. 9, 1959, Ser. No. 805,305

3 Claims. (Cl. 139—419)

This invention relates to curtain structures including draw and roll-up as well as shades and the like; more particularly to a novel construction providing for an attractive and serviceable textile material having a desired appearance, light weight, firmness, and light diffusion.

Light weight, sturdiness, serviceability, attractive appearance, economically produced, also light transmitting, are characteristics that are desirable in a curtain or shade. There are many available materials for draw curtains, window shades, coverings, roll-up drapes and cafe curtains. Some are made from finely cut split bamboo, from particular wood slatting, threaded beads, and a variety of rough textile weaves, as well as from metal slatting. The scope of use of any of the aforesaid is generally limited by the lack of adaptability to many uses and the cost in manufacture. This invention provides for a curtain or shade material having generally the aforesaid desirable structural and esthetic characteristics and flexibility to design, one that is economically produced, and one that is adapted to extensive usage in homes as well as in business establishments.

More particularly the applicant provides for a novel construction comprising a "man-made" straw-like monofilament held in proper spaced relation by a modified weave known as "leno" weave. The straw-like monofilament yarn advantageously can be regenerated cellulose, as viscose, since it is adapted to be economically produced, although any other artificially produced straw-like filaments, as singles or in bundle form, can be also used. Lateral or vertical rigidity or a sufficiency of it is attained through the particular spaced weave utilized. The leno weave construction provides firmness in support and for desirable spacing of the monofilament as well as for an enwrapment of them for preventing their displacement and insuring their position during use.

The straw-like filling material, depending upon spacing and size of bundle advantageously provides for whatever depth of shading of light transmission that is required. Furthermore, straw-like monofilaments as filling material, in a leno weave construction, attractively simulate a very fine bamboo structure yet also have the obvious and desirable flexibility of a textile material. Since it is constructed of a very light fiber that is maintained in a spaced relation it can be easily handled. Where the monofilaments are not dyed they provide for either a bright or a dull pearl-like finish which may be varied by contrasting weave material of cotton or other threads or yarns.

This novel material and its construction is more specifically described in the following specification and drawing where:

FIGURE 1 generally represents one form of a curtain structure adapted for roll-up uses;

FIGURES 2 and 3 taken along line 2—2 of FIGURE 1 and lines 2—2, 3—3 of FIGURE 5 represents in sectional detail a form of modified leno weave utilized in securing the straw-like bundles of viscose monofilaments;

FIGURE 4 represents an enlarged section of a viscose monofilament bundle taken through line 4—4 of FIGURE 3;

FIGURE 5 represents the weave construction taken through line 5—5 of FIGURE 2;

FIGURE 6 represents a double leno weave holding construction for bundles of viscose monofilaments; and

2

FIGURE 7 represents a standard leno weave construction.

Referring to the drawing, a roll-up type curtain 10 as shown in FIGURE 1 is advantageously made from a combination of bundles 11, shown in FIGURE 4, of generally flat straw-like monofilaments or strands made from a viscose spinning solution, securely tied at desirable spaced intervals by a weave known as "leno" weave. Bundles 11 of three, five, or more flat strands or monofilaments, depending upon denier and the light diffusion desired, are formed and fixed in position to form an open mesh structure. The viscose monofilaments are desirably tied as a yarn bundle of three to five or more filaments, each filament being not less than about 900 denier and the bundle about 4500 denier. These bundles 11 then are tied or leno woven securely in spaced relation to provide for a very attractive and novel fabric construction for use as a curtain or shade material. Where self support in the monofilament is a requirement it has been found that below about 900 denier a coating to stiffen the filaments would be necessary.

In the weaving trade a leno fabric is an open mesh, light weight cloth. The standard or common weave, also termed as doup or crossing threads, is shown in FIGURE 7. The holding threads 31 and 32 are passed over and under a filling or strand material 30 and simultaneously from side to side to form a crossed, interlacing or an interweaving holding construction, as in a zig-zag fashion, providing for a firm grip of the straw bundles. The weave advantageously firmly secures and compacts the bundle 30 holding it against displacement. Viscose straw, the filling material, is advantageous since it can be economically produced, it is firm and it is attractive in a curtain structure. However, because of its nature it is a slippery material and must be firmly secured against displacement. A modified form of leno weave has been found to provide the desirable holding construction as well as enhancing the final appearance of the finished product.

While the simple form of leno weave shown in FIGURE 7 can be utilized for many curtain applications the further modifications shown in FIGURES 2, 3, 5 and 6 are more desirable in curtain structures of the roll-up or draw type which are in frequent use for more strength, rigidity and appearance. In FIGURE 2 the straw bundle 11 is secured by a double or parallel leno weave 12, 13. The main threads 15 and 16 of the weave 13 (and also of the weave 12) run generally wavelike relative to each other, and over and under the bundle of straw monofilaments 11. At the same time about and from side to side the leno warps are being compacted by thread 17. This is more particularly shown in elevation in FIGURE 5 where the threads 15 and 16 undulate while thread 17 weaves and criss-crosses about the threads 15 and 16; also, as shown in FIGURE 6.

Depending on how much rigidity is required the weaves can parallel each very closely as in FIGURE 3, or they can be spaced as in FIGURE 2. By compressing the straw filaments at the holding points their free lengths tend to bow out being thus somewhat spread as indicated in FIGURE 6, filling in the space between the bundles 29. The leno weave 21, 22 and 23, 24 can add a further effect by being spaced or by being closely paralleling.

The use of viscose straw-like monofilament yarn 20 of at least 900 denier and higher as shown in FIGURE 6 provides for a construction which simulates fine bamboo slatting or wood slatting or of other materials without their disadvantage of solidity in form and their lack of translucency. Being of a sufficiently large denier the viscose monofilaments are sufficiently rigid to be utilized in many applications where bamboo and wood slatting are used.

They have the further advantage of light weight, ease of handling during construction; also, they can provide for a fabric material of any open mesh design having desirable light diffusion. The viscose monofilament material is readily dyeable, thus, giving a material adapted to a great range of decorative uses.

One form of construction, as shown in FIGURE 6, for a roll-up curtain that has been found advantageous has a leno woven double warp of colored (or white) cotton yarn on one inch spacing, the filling material being viscose straw yarn in bundles each comprising about 5 single monofilaments of about 1250 denier each (natural finish). A sturdy selvage finishes off the curtain. Of course, depending on requirements, monofilaments of greater than 1250 denier can be readily spun for greater bulk and rigidity.

Curtains or shades of any width can be produced since the straw fill is continuous in length. Looms of widths from 70 inches to over 100 inches can easily and readily produce the described material.

What is claimed is:

1. A woven fabric structure comprising, a weft of

spaced grouped pluralities of viscose monofilaments of continuous length, and a warp of spaced leno weaves.

2. A woven fabric structure comprising, a weft of spaced bundles of viscose monofilaments of continuous length having a generally flat cross-section and a warp of spaced leno weaves.

10 3. A woven fabric structure comprising, a weft of spaced bundles of generally flat viscose monofilaments of continuous length of not less than 900 denier each, and a warp of leno woven weaves spaced not less than about one inch apart.
